Related U.S. Application Data

The ornamental design for an architectural panel with embossed channel, as shown and described.

(63) Continuation of application No. 12/806,191, filed on May 3, 2010.

DESCRIPTION

(51) **LOC (9) Cl.** **25-01**

FIG. 1 is a front perspective view of an architectural panel with embossed channel shown used in a partition structure;

(52) **U.S. Cl.** **D25/138; D6/332**

FIG. 2 is an enlarged front perspective view of the central area shown in FIG. 1;

(58) **Field of Classification Search** **D25/111, D25/138-145, 150-153, 156, 157, 163, 199, D25/102-105, 110, 58; D5/20, 24, 32, 54, D5/4, 7; 156/63; 52/81.4, 81.5, 81.6, 747.1, 52/783.11, 311.1, 313, 311.2, 316, 239, 241, 52/481.2; 428/34, 34.1-34.9, 35.7, 36.1-36.4, 428/67, 446, 542.2, 542.6, 902, 904.4, 143, 428/147, 13, 332, 335, 336, 339, 480, 483, 428/195.1, 38; D6/332**

FIG. 3 is a left side sectional view taken along line 3—3 of FIG. 4;

See application file for complete search history.

FIG. 4 is a front elevation view;

(56) **References Cited**

FIG. 5 is a right side sectional view taken along line 5—5 of FIG. 4;

U.S. PATENT DOCUMENTS

FIG. 6 is a bottom sectional view taken along line 6—6 of FIG. 4;

FIG. 7 is a top sectional view taken along line 7—7 of FIG. 4; and,

FIG. 8 is a rear elevation view.
